UNITED STATES PATENT OFFICE.

GEORGE E. GREENWOOD, OF SAN FRANCISCO, CALIFORNIA, ASSIGNOR OF ONE-THIRD
TO HORACE M. WOOLLEY, JR., OF ALAMEDA, CALIFORNIA, AND ONE-THIRD TO
FRED N. VEDDER, OF SAN FRANCISCO, CALIFORNIA.

ADJUSTABLE FORM CLAMP.

Application filed May 10, 1922. Serial No. 559,808.

To all whom it may concern:

Be it known that I, GEORGE E. GREENWOOD, a citizen of the United States, residing at the city and county of San Francisco and State of California, have invented new and useful Improvements in Adjustable Form Clamps, of which the following is a specification.

This invention relates to improvements in clamps adapted for use in clamping together the separable parts of a concrete form or mold and is especially intended for use as a column clamp to lock together the forms within which concrete columns or the like are molded.

The object of the present invention is to generally improve and simplify clamps of the character described; to render the same adjustable for forms of varying size; to provide a clamp which may be quickly applied or removed, and to provide a wedge member by which the forms may be drawn up into snug engagement with relation to each other and the clamps rigidly secured. Further objects will hereinafter appear.

One form which my invention may assume is exemplified in the following description and illustrated in the accompanying drawings, in which—

Fig. 1 is a perspective view of the form clamp.

Fig. 2 is a side elevation of a column form showing the application of the clamp.

Fig. 3 is a cross section of Fig. 2 taken above the clamping members.

Referring to the drawings in detail, and particularly to Fig. 1, it will be seen that the clamp consists of two separable sections, as indicated at A and B, and that each section consists of a pair of arms 2 and 3, which are pivotally connected at one end as at 4. The arm 2 consists of a single bar of strap iron of suitable width and thickness, while the arm 3 consists of two superposed separated pieces of strap iron. These strips are separated at one end by introducing the strip 2 as shown at 4, and the opposite ends are maintained in a separated condition by means of spacers 5 and 6, secured by means of rivets or the like, indicated at 7. Such separation is more or less essential as the free ends of the arms are overlapped when the clamp is applied as shown in Figs. 2 and 3.

When applying a clamp of this character it is necessary that means be provided whereby the clamp sections can be tightly drawn together, and it is also necessary that the clamps be adjustable so that forms of varying size may be taken care of. With this end in view the pivotal connection formed between the respective pairs of arms is adjustable and this is accomplished by merely perforating or drilling the arms at spaced intervals as indicated at 8. To draw the arms or clamps together when applied, a series of teeth 9 is formed in the outer ends of the arms. These teeth are cut or punched in any suitable manner and are disposed on an angle of substantially 45° with relation to the bars or arms proper. These teeth are provided for the reception of wedges such as shown at 10 and 11 and these wedges are driven into place between the teeth when the clamps are applied.

In actual operation, referring to Figs. 2 and 3, C indicates a concrete column of suitable construction which may or may not be reinforced as the particular type of structure may demand, and 12, 13, 14, and 15, represent the respective sides and ends of the form. These forms are separable with relation to each other and are braced at intervals by means of cleats 16. The forms when assembled are in this instance tied together by the clamps, indicated at A and B, and these are preferably placed on top of the cleats 16 to secure the clamps against vertical movement on the forms. The arms 2 of the respective clamps are passed between the arms 3, as shown in Figs. 1 and 2, and the wedges 10 and 11, when introduced are tapped with a hammer or other suitable tool, thus causing the respective arms of the clamps to pull the form sections snugly together. After the clamps have been applied, it is obvious that the concrete may be poured and that the concrete will remain until sufficiently set. The clamps may then be removed whenever desired and the forms are stripped or removed with relation to the columns. This operation being quick and simple as the wedges are readily removed by merely tapping the lower ends thereof.

The several perforations 8 provided permit a considerable range of adjustment with relation to forms of varying size, and similarly the provision of the several teeth as

shown, that is the several teeth formed permit introduction of the wedges at any point desired.

One of the important features of the present invention is the shape of the teeth and the depth thereof. It will be noted that these teeth are placed on an angle of 45° and that the bottom portion of each tooth is square and disposed at an angle of 90° with relation to the sides of the teeth. This is important as it in reality forms opposed slots between which the wedges are inserted. The front of each tooth will in this manner engage one side of the wedge, while the back of each tooth will engage the opposite face of the wedge. The wedges are thus locked against accidental disengagement with the teeth and can only be inserted or removed by vertical movement of the wedges. The square shape of the bottom of each tooth is also of importance as it permits the formation of a wedge, the edges of which are right angular with relation to the respective faces of the wedge, thus giving a large bearing surface, and it further permits wedges of varying length and any desired taper to be employed.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

Having thus described my invention, what I claim and desire to secure by Letters Patent

is—

1. In a clamp of the character described pivotally connected arms, and teeth formed in the outer ends of the arms, said teeth having their side walls disposed on an angle of 45° with relation to the longitudinal axis of the arms, and the bottom of said teeth being square and disposed at an angle of 90° with relation to the sides of the teeth.

2. In a clamp of the character described a clamp section consisting of a pair of pivotally connected arms, one arm consisting of a single bar and the other arm of a pair of superposed bars, means for maintaining a predetermined spacing between said superposed bars, and means permitting longitudi-

dinal adjustment of the pivotal connection between the bars.

3. In a clamp of the character described a clamp section consisting of a pair of pivotally connected arms, one arm consisting of a single bar and the other arm of a pair of superposed bars, means for maintaining a predetermined spacing between said superposed bars, means permitting longitudinal adjustment of the pivotal connection between the bars, and teeth formed in the free ends of the bars and along the outer edges thereof, said teeth being disposed on an angle of 45° with relation to the longitudinal axis of the respective bars, and the bottom of each tooth being square and disposed on angle of 90° with relation to the sides of the teeth.

4. In a clamp of the character described, pivotally connected arms, teeth formed in the outer ends of the arms, said teeth having their side walls approximately parallel and disposed on an angle of approximately forty-five degrees with relation to the longitudinal axis of the arms, and a flat wedge member insertible between the teeth of opposite arms and guided thereby, said wedge being so formed as to have two faces approximately parallel and two converging edges engageable with the bottom of the teeth.

5. In a clamp of the character described, intersecting arms and teeth formed in the outer ends of the arms, said teeth having their bottom walls disposed on an angle of approximately forty-five degrees with relation to the longitudinal axis of the arms, and said bottom walls presenting substantially flat faces.

6. In a clamp of the character described, intersecting arms, teeth formed in the outer ends of the arms, said teeth having their bottom walls disposed on an angle of approximately forty-five degrees with relation to the longitudinal axis of the arms and presenting flat faces, and a flat wedge member insertible between the teeth of opposite arms, said wedge being so formed as to have two faces approximately parallel and two converging edges which present substantially flat faces and which are engageable with the bottom faces presented by the teeth.

GEORGE E. GREENWOOD
